UNITED STATES PATENT OFFICE.

FRANCIS A. MACNAB, OF GRANBY, COLORADO.

WAGON CONSTRUCTION.

Application filed March 10, 1928. Serial No. 260,583.

This invention relates to improvements in wagon constructions, and it consists of the combinations and arrangements herein described and claimed.

5 An object of the invention is to improve the reach bar of wagons, to which end the reach head of each reach bar is so designed as to not only afford maximum strength for a vulnerable point, but also provide the utmost freedom 10 of movement of the reach bar in characteristic directions.

Other objects and advantages appear in the following specification, reference being had to the accompanying drawing in which,

15 Figure 1 is a plan view of a wagon reach assembly, particularly illustrating the improved reach head,

Figure 2 is a perspective view of an end of the reach bar, again showing the reach head,

20 Figure 3 is a plan view of the reach head,

Figure 4 is a longitudinal section taken on the line 4—4 of Figure 1,

Figure 5 is a cross section taken on the line 5—5 of Figure 3,

25 Figure 6 is a detail section illustrating the latitude of rocking movement of the reach head without binding upon the king bolt.

Reference may be made to the Patent No. 1,588,323, granted for a wagon construction 30 on June 8, 1926, to Francis A. MacNab, the purpose of such reference being to afford a comparison of the reach head disclosed therein with the improved reach head which is the subject of the present application. It is 35 deemed unnecessary to make a comparison of each detail, for the present improvements of the reach head in the patent will speak for themselves.

Any one familiar with the use of a farm 40 wagon, to which the invention is dedicated, knows that the riding of the four wheels over an interrupted surface sets up great strains that are largely centered upon the king bolt. The necessity of providing for side rocking 45 motion in addition to horizontal pivotal motion of the reach bar has not escaped the attention of prior patentees. However, the lack of a well designed head has defeated the meritorious introduction of this important 50 adjunct to reach bars so that common practice is largely confined to a mere hole in the reach bar into which the king bolt is inserted.

First of all it is proposed to employ a tubular reach bar 1. Into one end of this reach 55 bar is inserted the closely fitting cylindrical shank 2 of the improved head that is gen-

erally designated 3. The employment of spot welding as indicated by the points 4 in Figures 2 and 4, makes a union between the two elements that is absolutely inseparable even 60 during abuse of the assembly.

As clearly seen in Figures 2 and 3, the head 3 is adequately enlarged to permit the cutting of an ample lateral slot 5. The lateral extremities of this slot taper to the point of 65 emergence with a hole 6 (usually round) for the king bolt 7. That part of the head 3 in which the hole 6 occurs is relatively thin at diametrically opposite points 8. However, the points of greatest thinness are confined to 70 diametrically opposite points in the direction of the slot 5 thus affording destructive portions that may in time be worn away by incessant action upon the king bolt as suggested in Figure 6.

75 The top 9 of the head 3 is flattened. The under side is flattened also, but the longitudinal portions are rounded at 10 upon such well defined arcs that the general aspect of the under side of the head is that of a round surface.

As a matter of fact, ample rounding is desirable, thereby permitting a most pronounced lateral rocking of the head in either direction in respect to the king bolt 7 without 80 imposing any undue strain either upon the king bolt or upon the rear portions of the wagon assembly. The front corners of the head are rounded at 11. The upper edges of the head are bevelled at 12. One purpose of 85 the rounding and beveling is to avoid sharp corners and edges. Another purpose of the bevels 12 is to effect a greater extent of side rocking of the head, before contact is made 90 with the sand board of the front wagon bolster, neither of which is shown.

An outstanding feature of the improved reach head is the great freedom of movement of the head between the sand board and front axle. The reach bar can be rocked to a surprising degree in lateral directions without 100 setting up any unusual destructive strain. The reader can imagine one of the rear wheels of a wagon having the improved reach head incorporated therein as running over a high 105 obstruction. The resulting tilting of the rear of the wagon gear will end at the king pin for the reach bar will merely rock sideways to the necessary extent.

Another advantage of the invention is discernible in the manufacture of the reach head. The reach head is made in one piece,

and the necessary operations thereupon can be reduced to a minimum. The assembly of the reach head with the reach bar ends with the mere insertion of the shank and the welding of a sufficient number of places.

While the construction and arrangement of the improved reach head is that of a generally preferred form, obviously modifications and changes may be made without departing from the spirit of the invention or the scope of the claims.

I claim:—

1. An article of manufacture comprising a shank having an integral expanded head thinner but broader than the shank, that is flattened on the top and under sides, the lon-

gitudinal portions of the under side being fully rounded to facilitate lateral rocking, the longitudinal edges of the top side being bevelled to afford a greater extent of rocking movement beneath the sand board of a wagon gear, said head having a king bolt opening.

2. An article of manufacture comprising a cylindrical shank insertable into a tubular reach bar and having an end expanded to form a reach head to be located beyond the adjacent extremity of said reach bar, said head having a king bolt opening.

Signed at Denver in the county of Denver and State of Colorado, this 17th day of February A. D. 1928.

FRANCIS A. MACNAB.
